EXPANDABLE REEL FOR RECEIVING WOUND FLEXIBLE MATERIAL

Murray Aaron Diamond, Ontario, Calif., assignor to
Sentinel Container Corp., Pomona, Calif.

Filed Oct. 12, 1971, Ser. No. 188,645

Term of patent 14 years

Int. Cl. D8—08

U.S. Cl. D8—220

FIG. 1.

FIG. 2.

FIG. 3.

FIG. 1 is a plan view of the expandable reel for receiving wound flexible material.

FIG. 2 is a side elevation showing the two flat discs of the reel in its non-expanded form.

FIG. 3 is a perspective view showing the reel in its expanded form, such that it is adaptable for receiving and storing wound flexible material.

We claim:

The ornamental design for an expandable reel for receiving wound flexible material, substantially as shown.
